RADIO DIRECTION FINDING

Edward Joseph Hefele, Lindenhurst, N. Y., assignor to Airplane and Marine Direction Finder Co., Lindenhurst, N. Y., a corporation of Delaware

Application June 17, 1932, Serial No. 617,793

4 Claims. (CL 250—11)

My invention relates to apparatus for and methods of operating radio receiving systems, and more particularly to apparatus for and methods of operating directional receiving systems used in direction finding and distance determination.

An object of the invention is to provide novel means for and methods of improving the directional characteristic of radio receiving systems, beyond that obtainable from the absorbing element itself.

Another object of the invention is to provide novel means for and methods of improving the directional sensitivity beyond that obtainable from the antenna itself of radio direction finders utilizing either the maximum or minimum signal method.

Still another object of the invention is to provide novel means for and method of obtaining as great a directional sensitivity when utilizing the maximum signal method as heretofore obtainable with the minimum or null signal method.

A further object of the invention is to provide novel means for securing any predetermined relation between the input and output voltages of a radio receiver used for determining direction or distance.

Still a further object is to provide novel means for varying the rate of change of the output voltage with respect to a predetermined rate of change of the input voltage in directional radio receiving systems.

A specific object of the invention is to provide novel means for securing any predetermined non-linear relationship between input and output voltages of a directional radio receiving system.

A still further object of the invention is to secure this result either in the receiver itself, in its associated indicator, or by a combination of the two.

Another object of the invention is to accomplish this result in radio direction finding or distance indicating receivers by means of automatic gain control, or by utilizing variable mu vacuum tubes having an exponential amplification factor, or by a combination of both.

Another object of the invention is to provide novel means for measuring distances between radio transmitting and receiving locations by more accurately indicating changes in the field intensity at the receiving or measuring location.

Other objects of the invention will appear in the detailed description of the invention given hereinafter.

Directional reception depends upon the non-

uniform directional absorbing power of an antenna. In polar coordinates, this characteristic is expressed by any diagram other than one having a constant radius.

The most common form of a directional antenna is the simple loop or symmetrical dipole. Its directional characteristic is expressed in polar coordinates by a figure 8 pattern. That is, the electromotive force induced in such an antenna when used for receiving radiant energy varies with the angular position of the antenna and direction as the cosine of the angle.

Another familiar form of directional antenna consists of a combination of a loop and non-directional vertical antenna. Its characteristic describes in polar coordinates a curve known as the cardioid or heart-shaped diagram. This system is known in the art as a uni-directional receiving system.

Another form of uni-directional antenna, commonly used in reception of short waves, consists of a series of spaced conductors or antennæ forming a so-called "antenna array". Its directional sensitivity is great in a given direction and small in all other directions and is expressed in polar coordinates by an elongated or exaggerated ellipse.

As described above, the directional characteristics depend on the change of radii in the polar diagram of the antenna. When the rate of change of the radii is great, the directional sensitivity is correspondingly great. Inasmuch as the rate of change of the radii is quite considerable at or near the null position and is very slight at or near the maximum position, the null method of direction finding has been used in preference to the maximum method.

To state this as applied to practical long wave direction finding, the accuracy of observation depends upon the sensitivity of the indicator to small changes in the electromotive force impressed upon it. This electromotive force varies with the angular rotation of the loop antenna used in such systems and is normally expressed by a sine curve in rectangular coordinates and by a figure 8 pattern, formed by two tangential circles of equal diameter, in polar coordinates.

This characteristic figure 8 pattern is used in direction finding by noting the direction of the loop antenna either when the signals are loudest or weakest, the former is known as the maximum method and the latter as the minimum or null method of direction finding.

From an inspection of the normal figure 8

8 pattern, it will be observed that for maximum signals, the radius of curvature is large so that there is a small rate of change of output voltage with variation in angular position of the 5 loop antenna. For minimum signals, the radius of curvature is small and, accordingly, there is a large rate of change of output voltage and variation in angular position of the loop antenna.

I have discovered that this rate of change obtained in the output of the receiver for both the maximum and for the minimum positions may be accentuated by varying the input-output voltage relationship in the receiving system or at the indicator or by a combination of both. This then 10 correspondingly accentuates the over-all characteristic of the entire system and increases the sensitivity of the readings at either the maximum or minimum positions.

When the null method is used, the figure 8 20 pattern is flattened by causing the input-output relationship of either the receiver, or indicator, or both, to vary non-linearly and in accordance with the expression:

$$25 (1) \quad \frac{\Delta E}{\Delta e} = X$$

where e =input voltage, E =output voltage, Δe =increment of input voltage, ΔE =increment of output voltage, and X is some variable that approaches zero as e increases; that is, the rate of change of output with respect to rate of change of input is made such that the ratio of rate of change of output to rate of change of input becomes smaller as the input is increased.

30 When the maximum method of reception, heretofore found unsuitable, is used according to my invention, the figure 8 pattern is elongated by causing the input-output relationship of either the receiver or indicator or both to vary non-linearly and in accordance with the expression:

$$25 (2) \quad \frac{\Delta E}{\Delta e} = X$$

45 where e =input voltage, E =output voltage, Δe =increment in input voltage, ΔE =increment in output voltage, and X is some variable that approaches infinity as e increases; that is, the rate of change of output with respect to rate of change of input is made such that the ratio of rate of change of output to rate of change of input becomes larger as the input is increased.

The invention will be made clearer from the 55 detailed description following, in connection with the drawings in which:

Figure 1 is a circuit diagram of one embodiment of the invention.

Figure 2 is a modified form of my invention in 60 which saturated transformers are used to carry out my invention.

Figure 3 is a curve drawn to polar coordinates showing the relationship between the various angular positions of a directional or loop antenna and the signal intensity as indicated on an output meter of the type described, in a system utilizing my invention.

Figure 4 is a modified form of my invention disclosing the use of automatic gain control in a receiver used in direction finding.

70 Figure 5 shows the curves of resistance to current density of copper oxide rectifiers used in one form of my invention.

Figure 6 consists of curves showing the instrument calibrations used in my invention.

75 Figure 7 illustrates the usual form of indicat-

ing instrument heretofore used in direction finder systems.

Figures 8 and 9 are diagrammatic views of my preferred form of indicating instrument, Figure 8 being used for maximum method and Figure 5 10 for null method operation.

Figures 10 to 27 are curves in both polar and linear coordinates showing the relation between antenna energy and indicator response obtained by using this improved system.

Figure 28 is a diagrammatic illustration of the change in wave shape of the received signal as it passes through the receiver to the indicator.

Figure 29 is a series of curves drawn to rectangular coordinates showing the shape of the 15 signal waves for different exponential values.

Referring to the drawings, I have illustrated in Figure 10 the figure 8 pattern drawn to polar coordinates illustrating the relationship between various angular positions of the loop and the energy absorbed; and in Figure 11 I have shown the same relationship drawn to rectangular coordinates.

As has already been explained, the normal loop 25 response curve heretofore used for direction finding may be represented either as a figure 8 consisting of two tangential circles of equal diameter as shown in Figure 10, or by a sine curve, as shown in Figure 11.

A similar figure 8 is obtained in the output of 30 the radio receiver when the rate of change of the output voltage with respect to the rate of change of input voltage is constant, as expressed in the Equation (1) when X =constant k , and 35 illustrated in Figure 12.

In this case, the curve of Figure 12 is a straight line so that the response of an indicator such as shown in Figure 7, connected to the output of the radio receiver, varies directly with the voltage applied to the radio receiver as indicated in Figures 14 and 15. Because the curvature is steep at or near the null position, the response is sharp, as indicated in Figure 13. This latter figure is drawn to rectangular coordinates and indicates the over-all response of the loop, receiver, and indicator for various angular positions of the antenna near the null. It has substantially the shape of the sine curve shown in Figure 13, the lower half of the wave being turned back on itself to indicate more clearly the sharpness of response.

In the case described above, a radio receiver having a straight line amplifying characteristic is used and a very much sharper null than a maximum is obtainable. In fact, there is no sharply defined maximum position.

In accordance with my invention, radio circuits and receivers are employed to produce a more sharply defined null position or, alternately, 60 a sharply defined maximum position. In one embodiment of this invention, it is accomplished by utilizing circuits having non-linear amplifying characteristics as, for example, by employing automatic gain control and variable mu tubes.

In Figure 4, there is disclosed one form of 65 automatic gain control. As will be well understood, input energy from a directional antenna (not shown) is applied across the control electrode of the first tube 1 through the tuned circuit 2, comprising the inductance 3 and variable condenser 4 connected across the loop. The output from the tube 1 is applied through the transformer 5 to the input of a detector or demodulator tube 6. The output from the tube 6 in turn 70

75

flows through the audio frequency transformer 7 to an audio frequency amplifying circuit 8, and thence to an indicator (not shown).

The output from the tube 1 is also applied 5 through the rheostat 9 to the input of a gain control tube 11. The grid of the control tube has applied to it a direct current voltage only. The cathode of the control tube is connected to the position 13 so that it has a more positive 10 bias than the grid. The tube is, therefore, normally beyond the plate current cut-off point, but as the detector tube cathode bias becomes more positive, the control tube 11 commences to draw plate current and effectively biases the grid of the 15 tube 1 in accordance with the carrier strength. To accomplish this, the cathode bias resistor 14 of the detector tube 6 has developed across it a voltage which increases as the carrier increases.

As the potential applied across the input of the 20 first tube increases, the gain control functions to decrease the amplifying characteristic by changing the grid potential of the tube 1. Similarly, other tubes than 1 may be controlled by this system if desired.

25 With this arrangement, the amplification characteristic or gain of the radio receiver becomes non-linear; that is to say, as expressed in Formula (1), X approaches zero since the gain is high for low voltage input and decreases as the 30 input voltage increases. This describes a curve, Figure 18. The resulting figure 8 is the deformed or flattened figure, illustrated in Figure 20. The steepness of curvature at or near the null position has been considerably increased and is 35 illustrated to better advantage by the rectilinear coordinate Figure 21. This increased steepness of curvature at the null has of course resulted in an increased flattening of the curve at its maximum. Thus, the system has become more 40 sensitive at or near the null and less sensitive at the maximum than has been heretofore obtained.

A sharpened null position response curve is indicated by Figure 19 wherein the indicator response increases rapidly with the slightest variation 45 from the null position.

Practical conditions conforming to the requirements of Equation (1) are easily obtained by the use of variable mu tubes having decreasing amplification constants for increasing grid potential. 50 These tubes may operate according to either an exponential or logarithmic law as follows:

Where X is less than 1, an exponential Equation (3)

$$(3) \quad E_{\text{output}} = e^X E_{\text{input}}$$

55 is obtained.

Where X is greater than 1, a logarithmic Equation (4)

$$(4) \quad E_{\text{output}} = \text{Log}_e X E_{\text{input}}$$

60 is obtained.

Both the above conform to the general conditions stated in Equation (1).

This characteristic can be further accentuated by the combination of variable mu tubes and 65 automatic gain control.

Although only one form of automatic gain control has been described for purposes of illustration, other forms of automatic gain control may be used in this invention.

70 Thus, for example, other well known automatic gain control systems may be used in inverted relation so that the gain of the receiver increases with increase in voltage impressed across the receiver. The gain of the radio receiver will then 75 be low for low voltage inputs and high for the

high voltage inputs, producing a response curve, as shown in Figure 24.

The figure 8 pattern is elongated as shown in Figure 26 so that the receiving circuit's sensitivity at the maximum is much greater than in Figure 14 and particularly the flattened figure 8 pattern of Figure 20. This is more clearly shown when drawn to rectangular coordinates in Figure 21, wherein the maximum is shown sharply defined. A more sensitive response at the maximum is thus obtained at the expense of sensitivity at the null as shown diagrammatically in Figure 25.

In the above, circuit arrangements have been described for increasing the sensitivity at the 15 null and at the maximum. As is well understood, the maximum method is much preferred to the null method but has not been extensively used because of lack of clear definition of the maximum. According to this invention, the maximum 20 now becomes so sharply defined that it can be used, in practice, with the same degree of accuracy as the null method. Other circuit arrangements and mechanisms for carrying out this invention also may be used. 25

In Figure 1, I have schematically shown a loop antenna which is rotatably mounted on a vertical spindle (not shown) to permit rotation thereof in a manner now well known in the art. The tuned antenna circuit is connected across the input terminals of a radio frequency amplifier, the output of which is connected to a detector which in turn is connected to an audio frequency amplifier. This is now well known in the art and accordingly is illustrated diagrammatically. 30

The output current from the audio frequency amplifier is applied in turn through the system of rectifiers 16 to the indicating instrument 15. As shown, the rectifiers 16, which may be of the copper oxide type, are connected in a Wheatstone 40 bridge arrangement, the indicating instrument 15 being connected across the bridge. The positive half of the pulsating current in the output circuit of the audio frequency amplifier flows through the rectifier system 16, in one direction only to 45 the instrument 15. The negative half of the pulsating current flows from the output of the audio frequency amplifier through the rectifier 16 in the opposite direction and in the same direction as the first half cycle through the instrument 15. 50 Both halves of the rectified currents thus flow through the instrument 15 in the same direction.

Because of the comparatively large power consumption and delicacy of alternating current measuring instruments, such as thermal, iron vein 55 and dynamometer types, measuring instruments for direction finding equipment are inherently confined to the direct current rectifier types. These have been found to be more rugged, producing full scale deflection with currents of 1 to 2 60 milliamperes. These output measuring instruments are connected to the radio receiving circuit through a rectifier as, for example, vacuum tube type or copper oxide type of rectifiers.

However, the resistance of solid rectifiers 65 change for different current densities per square centimeter of rectifier; the resistances being quite large for current densities in milliamperes per square centimeter, decreasing rapidly as the current density is increased at first and thereafter 70 decreasing slowly.

Thus, as shown by the curve in Figure 5, as the current through the rectifier is increased from 0 to 4 or 5 milliamperes, per square centimeter, the rectifier resistance decreases first very rapidly 75

then more slowly from infinity to about 800 or 1000 ohms for a $\frac{1}{16}$ inch rectifier. As the current is further increased to 50 or 60 milliamperes per square centimeter, the resistance falls more and more slowly to about 500 to 600 ohms.

Inasmuch as the scale of the instrument connected to the rectifier depends upon the relation of its resistance to the resistance of the rectifier, this change in ohmic resistance with a change of current density flow through the rectifier must be taken into consideration. The rectifier type of alternating current instruments are found to have a true uniform scale only when the resistance of the rectifier unit forms a negligible part of the total instrument resistance. As the rectifier resistance approaches the instrument resistance in value, the lower end of the scale becomes somewhat crowded or narrowed.

For example, in the case of a 5 volt instrument of 1000 ohms per volt sensitivity, the current flowing through the rectifier at full scale deflection is 1 millampere. For this current, the rectifier resistance is in the vicinity of 1000 ohms. But at one volt when the current through the rectifier is only about a fifth of a millampere, the rectifier resistance is 2000 ohms. Therefore, for one volt, the total instrument resistance has increased from 5000 to 6000 ohms. The impressed potential of one volt will therefore cause less than one-fifth of the deflection produced by the five volts.

In voltmeters with ranges of about 15 volts and with reasonably high sensitivity, the non-linearity of the scale is negligible. As either the range of sensitivity is increased, the non-linearity becomes more marked until at ranges of about 2 or 3 volts, it is found that about one-quarter of the scale measures a third of the full scale voltage.

This is exactly the opposite of what is desired with the null method of direction finding. As hereinbefore explained with the null method, the near zero indications should possess maximum sensitivity and instead of one-quarter of the scale measuring a third of the full scale voltage changes, the exact converse is desired.

This is obtained by constructing the indicating instrument as shown in Figure 9. As shown, there is provided a pivotal armature 15 carrying a pointer 16 operating over a graduated scale 11. In operative relation with the armature 15 there are provided two pole-pieces 18 and 19. These pole-pieces 18 and 19 are pivotally mounted, as shown at 20 and 21. The edges 22 and 23 of the pole-pieces 18 and 19 opposite their faces 24 and 25 are in engaging relation with the pole extension 26 which completes the magnetic circuit through the armature and airgap.

Pole-pieces 18 and 19 may be angularly displaced about their pivots 20 and 21 to any desired degree in either direction by a manual adjusting screw or lever connected thereto. Preferably pole pieces 18 and 19 are controlled simultaneously by a common member, as for example 27, so that the two pole pieces will be displaced clockwise or counter-clockwise simultaneously and through the same angular displacement.

Thus, for example, the pole-pieces may be made to assume the position shown in Figure 9 in which the lower end of the pole-piece 18 has been moved away to increase its airgap. Simultaneously, the pole-piece 21 has been displaced so that its upper end has been brought close to the armature to reduce the airgap therebetween while the lower end has been moved away to increase the airgap there.

It should be noted that the edges 22 and 23 are

sloped to form the arc of a circle with 20 as its center and that the edge of the pole-piece 26 in cooperation therewith has a similar arc shaped edge so that as the pole pieces 22 and 23 are moved about their pivots 21, the edges 22 and 23 remain continually in engaging relation with the pole-piece 26 to maintain a minimum reluctance of this magnetic path thereat.

With the pole pieces rocked, as shown in Figure 9, and the gaps at the edges 28 and 31 reduced to a minimum, the reluctance of the magnetic path including the pole-pieces, armature, and the air-gaps, is a minimum while the pointer deflection is near zero.

When now the current through the receiving instrument is increased slightly, there is a change in the magnetic lines of force which produces a corresponding deflection of the pointer through a predetermined angle in accordance with the change in current flow.

Assuming now that the instrument pointer is nearer the end of the scale at its maximum deflected position, the armature is now in the position opposite the pole ends 29 and 30 where the gap is at a maximum. A corresponding change in current flow through the instrument at this position will not produce as large a change in the magnetic lines of force and accordingly the change in deflection for this change of current will not be as large as was the case for a similar change in current at or near the zero position of the instrument.

In other words, the instrument is more sensitive at or near the zero position and becomes increasingly less sensitive as the armature and pointer approach the maximum position. A substantially logarithmic response is thus effected. An exponential response where X is less than one may also be effected.

The characteristic of the rectifier by which its resistance decreases with increase in current density may be applied with advantage to the maximum method of direction indication since in the latter method the maximum sensitivity is desired at or near the maximum readings. This advantage may be further accentuated by using the copper oxide rectifier system described in connection with Figure 1 with the indicator shown in Figure 8.

As illustrated in Figure 8, the adjustment is such that the ends 29 and 30 are so placed as to secure a minimum airgap for maximum deflection and a maximum airgap for zero deflection. The instrument then responds exponentially where X is greater than 1.

The type of indicator shown in Figures 7 to 9 may be used with the usual type of radio receiver as shown, for producing either a logarithmic or exponential response; or if desired, may be used with special circuits for exaggerating these effects. Thus, the logarithmic indicator, Figure 9, may be used with a sensitivity control circuit including variable mu tubes as shown in Figure 4 for producing logarithmic response, or an exponential response to a more negative power. The exponential indicator of Figure 8 may be used with an exponential receiving circuit to produce higher powered exponential response than obtainable by either receiver or indicator individually. Although visual indicators are shown, it will be obvious to those skilled in the art that audible signal indicators may be used.

Figure 29 discloses a family of curves drawn to rectilinear coordinates. These curves illustrate how the normal response curve may be dis-

torted at will to produce any desired degree of sharpness at either the maximum or minimum by the use of the exponential law alone, as given below:

$$E_{\text{output}} = eX_{\text{input}}$$

in which X may be equal to greater than or less than unity. The case in which X is greater than unity corresponds to the Equation (2) and the case in which X is less than unity corresponds to Equation (1).

Curve e is a pure sine wave obtained when $X=1$ and is the output obtained in the directional systems heretofore used, when connected to a normal loop and a linear indicator. Curves f , g , h , show how the receiver output according to the invention is distorted to increase the null sensitivity by Equation 3 where X is equal to -2 , -4 and -8 , respectively.

Curves a , b , c , and d show how the receiver output is distorted to increase the maximum sensitivity by Equation 4 where $X=16$, 8 , 4 , and 2 , respectively.

In the following, the values used in plotting these curves are tabulated:

Degrees	$\sqrt{E}$	$\sqrt{E}$	E	E^2	E^4	E^8	E^{16}
	%	%	%	%	%	%	%
0	0	0	0	0	0	0	0
1	26.5	13.3	1.74	.03	.009	81×10^{-4}	64×10^{-13}
5	51	29.4	8.7	.75	.056	.003	9×10^{-3}
10	62.5	41.5	17.26	.2	.008	.008	64×10^{-3}

90	100	100	100	100	100	100	100

Figure 2 illustrates a further circuit modification of my invention. In this embodiment of my invention, a rotatable loop antenna and radio receiver circuit similar to that described in connection with Figure 1 is employed. In place, however, of the special indicator, I provide a special transformer construction for producing a logarithmic response reading in a linear indicator. In accordance with this embodiment I provide an oscillator such as, for example, a 50 cycle oscillator 40 connected across a 6000 ohm resistance. Connected across 50 ohms thereof are the leads 41 and 42 extending in series through the primary windings 43 and 44 of the two transformers 45 and 46. The secondaries 47 and 48 of the two transformers 45 and 46 are also connected in series and through a vibration galvanometer 49.

The pair of transformers is assembled and placed one in each compartment of an iron screening box, preferably set in paraffin wax. The secondaries are wound so that when connected in series, as shown, they have the necessary direct current resistance to damp the galvanometer constant with the rapid response and also have a reactance not exceeding the direct current resistance of the circuit.

By providing the proper ohmic resistance at 41 in series with the primary, the current in the primary of the transformer is not affected by the change in the magnetization of the core. The secondary impedance is not affected by changes in magnetization of the core and the necessary

high series impedance is supplied by the galvanometer. The magnetization force in all parts of the iron is substantially proportional to the current which flows in the saturation winding assuming no magnetic leakage.

The current to be measured is received over the loop antenna 1 connected to the receiver 50. The output from receiver 50 is, in turn, connected to the primary of transformer 51, the secondary of which is in turn connected to the 10 anodes of a full wave gas filled rectifier tube such as tube 52. Tube 52 comprises an envelope enclosing anodes 53 and 54 and a common cathode 55. The cathode 55 is heated from a source 56 controlled by resistance 57. Extending from the 15 mid-point of the secondary of transformer 51 is the lead 58 connected to the two auxiliary saturating windings 59 and 60 of transformers 45 and 46, respectively.

It is an obvious advantage to have no coupling 20 between either the primary or secondary windings and the saturation coil which might result in the latter feeding back into its source of supply. Consequently, each primary and secondary may, if desired, be wound in two halves, one half 25 of each being assembled on each of the outer limbs of the transformer core.

The current in the transformer secondary from the oscillator 40 is increased and decreased as the amplitude of the measured current in windings 59 and 60 varies. As the measured current saturates the transformer, the induced currents in the secondary from oscillator 40 decrease in primary amplitude. Accordingly, the indication of the galvanometer varies inversely as the input or measured current varies.

Figure 6 is a curve showing the deflection against $\log_1$, 1 being the variable currents applied across the saturation coil from the full wave rectifier. It will be observed that there is an approximately straight portion in the curve, above and below which the rate of change of D with $\log_1$ is very small. On reducing the current 1 from maximum to zero, a slightly different path is followed by the $D/\log_1$ curve from that taken for ascending values of 1 due to hysteresis. This effect, however, is only slight and not of much importance.

Although I have illustrated my invention by the preferred forms of radio receivers and indicators, it will be obvious to those skilled in the art, that other means for and methods of varying the ratio of input voltage to output voltage may be employed and are part of my invention. Furthermore, my invention may be applied to 55 directional and distance finding systems as well as direction finding, and I do not intend to limit myself except as set forth in the appended claims.

I claim:

1. In a directional system including a directional antenna, amplifier, and an indicator, the method of directional reception comprising receiving variable amounts of radiant energy in accordance with the position of the directional antenna with respect to the direction to the source of said radiant energy; impressing the received energy across the input of the amplifier; amplifying the impressed energy in accordance with a non-linear exponential law such that as the input energy impressed on the amplifier from the 70 directional antenna varies in accordance with the direction of reception of the signal, the output of said amplifier will form a figure 8 which is substantially flattened as compared to the normal circle figure 8; and impressing said variable out- 75

put signals from said amplifier directly on the indicator whereby the indicator response is more pronounced for predetermined changes in the input at the null of the figure 8 than in the case 5 of a circular figure 8.

2. In a directional system including a directional antenna, amplifier, and an indicator, the method of directional reception comprising receiving variable amounts of radiant energy in accordance with the position of the directional antenna with respect to the direction to the source of said radiant energy; impressing the received energy across the input of the amplifier; controlling the amplification by controlling the 10 volume so as to amplify the impressed energy in accordance with a non-linear exponential law such that as the input energy impressed on the amplifier from the directional antenna varies in accordance with the direction of reception of 15 the signal the output of said amplifier will form a figure 8 which is substantially flattened as compared to the normal circle figure 8; and impressing said variable output signals from said amplifier directly on the indicator whereby the 20 indicator response is more pronounced for predetermined changes in the input at the null of the figure 8 than in the case of a circular figure 8.

3. In a directional system, a directional antenna; an amplifying circuit having an input 30 and an output; means for connecting the input of said amplifier to said directional antenna; said amplifier comprising means for impressing thereon variable amounts of radiant energy in accordance with the position of the directional antenna with respect to the direction to the source 35 of said radiant energy; said amplifier including means for amplifying the impressed energy in accordance with a non-linear exponential law over the entire range of amplitude variations produced by all positions of the directional antenna 40

such that as the input energy impressed on the amplifier from the directional antenna varies in accordance with the direction of reception of the signal the output of said amplifier will form a figure 8 which is substantially flattened as compared to the normal circle figure 8; an indicator; and means for impressing said variable output signals from said amplifier directly on the indicator whereby the indicator response is more pronounced for predetermined changes in the 10 input at the null of the figure 8 than in the case 15 of a circular figure 8.

4. In a directional system, a directional antenna; an amplifying circuit having an input and an output; means for connecting the input of said 20 amplifier to said directional antenna; said amplifier comprising means for impressing thereon variable amounts of radiant energy in accordance with the position of the directional antenna with respect to the direction to the source of said 25 radiant energy; said amplifier including means for controlling the amplification by volume control so as to amplify the impressed energy in accordance with a non-linear exponential law over the entire range of amplitude variations produced by all positions of the directional antenna such that as the input energy impressed on the 30 amplifier from the directional antenna varies in accordance with the direction of reception of the signal the output of said amplifier will form a figure 8 which is substantially flattened as compared to the normal circle figure 8; an indicator; and means for impressing said variable output signals from said amplifier directly on the indicator whereby the indicator response is more 35 pronounced for predetermined changes in the input at the null of the figure 8 than in the case of a circular figure 8.
